ULTRA-VIOLET LAMP OR SIMILAR ARTICLE

Frederick Gordon Mackay, Tarzana, Calif., assignor to Ultra-Violet Products, Inc., San Gabriel, Calif., a corporation of California

Filed Sept. 17, 1962, Ser. No. 71,729

Term of patent 14 years

(Cl. D48—20)

FIG. 1 is a front perspective view of an ultra-violet lamp or similar article, showing my new design;

FIG. 2 is a side elevational view thereof;

FIG. 3 is a back elevational view thereof;

FIG. 4 is a top plan view thereof; and

FIG. 5 is a bottom plan view thereof.

The broken line showing of a fragmentary cord in FIGS. 2 and 3 is for illustrative purposes only.

I claim:

The ornamental design for an ultra-violet lamp or similar article, substantially as shown and described.
